ILLUMINATED VANITY CASE

George M. Cressaty, New York, N. Y.

Application June 14, 1938, Serial No. 213,675

15 Claims. (Cl. 240—6.45)

This invention is directed to a vanity case or the like made up in sections, with the sections mounted for relative swinging movement, and including a lighting unit which is automatically energized and deenergized in accordance with a predetermined swinging relation of the sections.

The primary object of the invention is the provision of a vanity case which includes a body section in which the cosmetics are placed, and a cover section carrying a lighting unit and mirror, the respective sections being mounted for relative swinging movement to move the body section in aligned interfitting relation with the cover section to form a compact article, or to move the body section at any angle to the cover section to expose the mirror for use.

A further object is the provision, in the type of vanity case described, of a lighting unit, together with means for energizing the lighting unit in a predetermined swinging relation of the sections, in order that the user, by relatively swinging the sections to a definite position, may obtain the use of artificial illumination to assist in make-up.

A further object is the provision of an element of the energizing control of the lighting unit which may be arranged in any one of a number of different positions, whereby the energizing of the lighting unit may be perfected in any angular relation of the sections, or when the sections are extended in aligned relations. This permits the particular vanity case to be constructed to permit the energizing of the lighting unit in any relative swinging position that may be desired in the completed article.

A further object of the invention is the provision of a vanity case in which the sections are mounted for swinging movement, with the cosmetic-carrying receptacle on the body section conveniently accessible to the user in any position of the parts, whether fully closed, fully opened, or at any intermediate position.

The invention, in the preferred form of details, is illustrated in the accompanying drawings, in which:

Figure 1 is a plan view of a vanity case constructed in accordance with the invention, with the parts shown in closed positions;

Figure 2 is a similar view, with the parts shown in fully open relation, the closure for the lighting unit being omitted to show the arrangement of the parts of such unit;

Figure 3 is a section on the line 3—3 of Figure 2;

Figure 4 is a perspective view of the parts of the vanity case, shown separated;

Figure 5 is a broken plan view of the cover section, the connected body section being shown in dotted outline at an angle to the cover section;

Figure 6 is a perspective view of the circuit closing disk forming part of the swinging joint between the sections;

Figure 7 is a diagrammatic view of the circuit for the lighting unit;

Figure 8 is a plan view of the vanity case showing a modified form of the invention;

Figure 9 is a broken enlarged plan view, partly in section, illustrating more particularly the control of the circuit for the lighting unit;

Figure 10 is a sectional view on the line 10—10 of Figure 8;

Figure 11 is a section on the line 11—11 of Figure 8;

Figure 12 is a longitudinal section through the vanity case, with the parts in closed relation;

Figure 13 is a broken perspective view of the vanity case, with the movable sections approaching closed positions; and

Figure 14 is a longitudinal sectional view of the lighting unit, the section being taken on line 14—14 of Figure 8.

The vanity case, in the construction shown in Figures 1 to 7, inclusive, includes what will be termed a cover section 1 made up of a base plate 2, formed at one end with an outstanding housing 3 for the lighting unit, and centrally of the opposite end with a projecting ear 4, formed with a pivot opening 5.

A body, or cosmetic-carrying section 6, is in the form of a hollow receptacle, the transverse dimension of which is substantially that of the cover section, but with a reduced longitudinal dimension. The upper wall of the body section is formed with an opening having a door 7 to permit access to the cosmetics in the receptacle, and this receptacle is formed, next the lower wall, with a threaded enlargement 8.

The sections are connected for relative swinging movement through a pivot pin 9, which is passed through the opening 5 in the ear 4 of the cover section and threaded into the enlargement 8. A switch disk 10 is mounted on the pin between the ear 4 and the enlargement. This disk is of insulating material and is provided with an embedded contact section 11, the surface of which is in the peripheral plane of the disk.

The lighting unit, which is arranged in the housing 3, includes batteries 12 and a light source

12^a, said light source a socket and a lamp, the former being grounded at 12^b. The circuit for the light source includes conducting bars 13 and 14, the former of which leads through one battery 12, which is grounded at 13^a. The bar 13 is also connected to the other battery 12 and the latter grounded at 13^b. The bar 14 leads to the lamp of the light source. Fig. 7 shows a diagram of the circuit between the batteries and lamp. The bars 13 and 14 extend lengthwise of the cover section, and at the end remote from the lighting unit are turned laterally and terminate in spaced contact ends 17 arranged in the path of movement of the embedded contact section 11.

As the switch disk may be arranged in any angular relation to the enlargement 8 in any particular vanity case, the angular positions of the body section at which the lighting unit may be energized may be arranged as desired in the particular case. It is an important feature of the invention that this adjustment permits any angular relation of the body section to be selected as that where the lighting unit may be energized. In other words, the control of said unit may be such as to energize the light source at any relation of the parts other than when closed.

The end of the lighting unit housing 3 is preferably of arcuate outline, as indicated at 18, and the free end of the body section is similarly formed, as at 19. Thus, when the sections are swung into aligned closed relation, the meeting ends interfit, as shown in Figure 1, to improve the appearance and render the vanity case as a whole more compact.

The wall of the lighting unit housing 3 is formed to receive a lens 20, to increase the intensity of the light from the miniature bulb necessarily employed, and to control the spread and direction of the beam for proper and direct illumination of the face of the user. The upper face of the base plate 2 below the housing 3 is formed or provided with a mirror 21, which is, of course, exposed for use when the body section is swung from its closed relation to the cover section.

In the form shown in Figures 8 to 11, inclusive, the vanity case of this invention is shown in slightly modified form. Here the mirror section 22 is formed as a flat plate 23, with an outstanding box-like receptacle 24 at one end and with a door 25 hinged at 26.

Two swinging sections are connected to the cover section, one such swinging section, as 27, forming a battery case, and the other such section, as 28, forming a cosmetic-carrying section. The end of the mirror section opposite the receptacle is formed with a pivot extension 29, arranged similar to pivot sections 30 and 31 of the respective sections 27 and 28. The sections 27 and 28 are formed as U-shaped sections in transverse section, with their open sides uppermost in the positions shown in Figure 8. These open sides permit the sections 27 and 28 to telescope over the mirror section, as shown in Figure 13, the outer walls of the sections 27 and 28 fitting more or less snugly against the outer face of the plate 23 of the cover section, and the inner or upper walls of the sections 27 and 28 being spaced sufficiently from the outer walls to permit such upper walls to fit more or less snugly over the receptacle 24 when the case is closed. The dimensions of the sections 27 and 28 transversely of the vanity case are approximately one half that of the mirror section 22, so that when the sections 27 and 28 are in folded or closed

relation they completely inclose the mirror section 22 and overlie the door 25, to hold the same in closed relation.

Mounted on the interfitting pivot sections 29, 30, and 31 is an insulating cup 32, the annular wall 33 of which is formed through its length with a slot or recess 34, which may open through the upper edge of the cup, but does not extend through the bottom thereof. A pivot pin 35 passes centrally through the bottom of the insulating cup and through the interfitting sections 29, 30, and 31 to swingingly support the sections 27 and 28 relative to the cover section 22, a nut 36 securing the inner end of the pin against outward movement.

A lamp socket 37 is carried by the outer end of the pivot pin 35, so that one terminal of said socket is grounded for circuiting provisions. The opposite terminal of the lamp socket is connected through a strip 38, engaging such terminal and extending through a channel 39 in the side wall, which leads within the lower end of the annular recess 34. The terminal of the strip 38 extends across and forms a contact abutment 40 in the recess 34, as shown more particularly in Figure 9.

The section 27 forms the lighting unit, and receives batteries 41 and 42, one terminal of battery 41 being grounded and the other connected by a strip 43 with a non-similar terminal of battery 42. The opposite terminal of battery 42 has a conducting strip 44 which extends to the recess 34 of the insulating cup 32, and is provided with a contact end 45, curved concentrically with the recess 34 and designed to fit movably in such recess.

The lamp is thus in circuit with the batteries, with the latter in series, said circuit being closed when the section 27 has been swung to a point to cause the contact end 45 of the strip 44 to contact with the contact abutment 40. With the section 27 in other positions, for example when it is in closed position, the lamp circuit is of course open and the circuit is not energized.

The section 28 is designed to carry the desired cosmetics, and is formed interiorly with a box-like holder 46 opening through one side wall of the section and provided with a door 47 to permit access to the cosmetics. The section has a bar extension 48 terminating in a plate-like end 49, similar to the plate-like contact 45 of the section 27. The plate-like end 49 also seats movably in the recess 34, the terminal of the end 49 being provided with insulation to avoid electrical connection with the abutment contact 40. The plate-like ends 45 and 49 of the sections 27 and 28 will, when moved to contact with the contact abutment 40, be limited in further opening movement, and in this position the lamp will be energized.

Uninterrupted spaces 50, in the lighting unit section 27, and 51, in the body section 28, are provided below the batteries and cosmetic holder to permit closing movement of these sections without interference from the plate 23 of the cover section, and both the batteries and cosmetic holder are sufficiently spaced from the free ends of the sections 27 and 28 to provide for reception of the box 24, when closing the parts.

The plate 23 of the cover section is formed or provided with a mirror 52, which is exposed when the sections 27 and 28 are open and covered when such sections are closed. The receptacle is designed for the reception of any articles which one may desire to carry with the vanity case,

It is, of course, apparent that either section 27 or 28 may be swung to open position independently of the other, and this permits the user, merely by opening the section 28, to expose a part of the mirror and position the cosmetic holder for convenient use. Where the section 27 is opened alone, the light is energized and may be used for any purpose. With both sections opened, the light is energized and the cosmetic holder conveniently available. It is also to be noted that, with the vanity case held in a natural position, either or both of the sections 27 and 28 will swing to open position by gravity, and remain in open position under gravitational influence until manually closed. Of course, in this type of case it is impossible to use other than miniature lamps and batteries, and, as experience has proven that the light from such source is inefficient, it is of importance that controlled and adequate light be provided. To this end, the upper end of the insulating cup 32 is provided with a lens 53, which is particularly designed to collect the light and control the spread of the beam to afford maximum light in a beam shaped and concentrated for lighting the face of the user. The lens also serves to close the upper end of the slot or recess 34 to prevent accidental separation of the parts movable in such recess, as more particularly shown in Figure 11.

It will be apparent from the above description that, in the form illustrated in Figures 1 to 7, the lighting unit is energized in some predetermined angular relation of the body section with the cover section, so that when the body section is in any other angular relation to the body section the lighting unit is not energized. Of course, by properly positioning the insulating disk 10, the angular relation of the body and cover sections at which the light is energized may be selected as desired, so that the user of the vanity case may swing the body section to that preselected position in which the circuit is complete and obtain artificial illumination to aid in her make-up, while if such artificial illumination is not desired a change in the angular relation of the body and cover sections will deenergize the lighting unit.

It is to be noted that, without intending any limitation, the control of the light source may be more conveniently so arranged as to energize such source when the parts are substantially in the relations shown in Figure 5, where the body section is at an angle to the cover section. If the light source is energized in substantially this relation of the parts, there will be a definite movement on the part of the user to secure the energization of the light source. In ordinary daytime, the user swings the parts to an aligned position, as in Figure 2. This is the natural position, and in this position there will be no energization of the light source. If artificial illumination is required, the user will slightly move the body section from the naturally aligned positions of the parts to an angular position, as shown by 6' in Figure 5, and the light results. This tends to a more natural and comfortable use of the vanity case and of the light source.

While in both forms of the invention illustrated and specifically described, the respective sections are mounted for a swinging movement in substantially parallel planes, it will nevertheless be obvious that the sections may be otherwise connected for swinging in different planes. In other words, the connecting means between the sections may be so arranged that the sections

hinge relative to each other in the nature of a book, or may be pivoted so that they move in relatively non-parallel planes. Under a hinged movement, and particularly in connection with the forms shown in Figures 1 to 7, the insulating disk will be caused to move with the body member, so that its contact section is swung into the path of movement of the terminals of the contact bars of the lighting unit.

It will be further understood that, while a swinging movement is preferred, the term "swinging element," as employed, is intended to cover the connecting of sections so as to cause their relative movement either as swinging in substantially parallel planes or as hinged for movement in planes approaching and receding from each other. Thus, the term "swinging" includes hinged connection as well as pivotal connection, to provide for the relative movement of the sections to insure the automatic energization and deenergization of the lighting unit in accordance with the relative degree of movement of the sections.

While a detailed portrayal has been given of some of the forms the invention may take, in the optical as well as in its mechanical characteristics, it is not intended to limit the invention to the above description. The nature of the invention is such that it may be applied in connection with a multitude of different uses. The invention may be used in connection with a multitude of compacts, vanity cases, cigarette cases, hand bags, lip stick or any other cosmetic carriers of different shapes or sizes. Various modifications and changes, or rearrangement of parts, may be made without departing from the spirit of the invention and the scope of the appended claims.

What is claimed as new is:

1. A vanity case comprising two sections, a lighting unit, a pivot connection between the sections to provide for their having relative swinging movement in substantially parallel plane and annular means about said pivot containing a portion of an electrical switch which is controlled in the movement of one section to energize the lighting unit when it has reached a predetermined position with respect to the other section.
2. A vanity case including a lighting unit, a cover section, a body section, means connecting the sections to permit both sections to swing in substantially the same plane about a single axis, and a substantially annular member of electrical insulating material having an electrical conducting element concentric with said axis and movable with and in response to the movement of the body section to automatically control the energization and deenergization of the lighting unit.
3. A vanity case including a lighting unit, a body section, a cover section, means for connecting the sections to permit their swinging movement, and an insulating disk mounted on the connecting means and fixed with relation to the body section, said disk having a contact strip and circuit terminals for the lighting unit arranged in spaced relation in the path of movement of the contact strip of the insulating disk.
4. A construction as defined in claim 3 wherein in the insulating disk is adapted to be secured to the body section to provide varying positions of the contact strip whereby the closing of the circuit for the lighting unit may be perfected in

any angular position of the body section with respect to the cover section.

5. A vanity case including a mirror section, two cover sections, and means for connecting all of the sections and permitting the covers to cover the mirror section when the parts are in closed position and a light source mounted on the axis of said means.

6. A vanity case including a lighting unit and a plurality of sections movable to open and closed positions, two of such sections being movable on a single pivot arranged in the longitudinal median line of the case to independently interfit with and together enclose a third section containing a mirror to provide a unit substantially the size of such third section.

7. A vanity case including a mirror section, two cover sections, and means for connecting all of the sections for relative swinging movement, the two cover sections moving outwardly relative to each other in their opening movement and a light source located on the axis of said means.

8. A construction as defined in claim 7 wherein the connecting means is in the form of an insulating cup and pivot pin, the light source disposed within the cup and a switch in communication with the lighting unit and movable in the insulating cup to close an electrical circuit when one of the cover sections has reached a predetermined open position.

9. A vanity case including a mirror section, substantially duplicate cover sections, one for holding a source of electrical energy and the other for holding cosmetics, a pivot pin uniting the sections to permit them to swing in substantially parallel planes, an insulating cup arranged about the pivot pin and formed with an annular recess, a lamp socket carried within the insulating cup and having a conducting strip terminating in said recess, a contact plate forming part of a circuit operating in the recess in the cup whereby in a predetermined swing movement of one of the cover sections the circuit will be closed.

10. A vanity case having sections, the sections being pivotally connected for swinging in substantially parallel planes, a mirror in one of such

sections, a light source, energizing means therefore, and means carried by the pivotal connection and responsive to relative swinging movement of the sections to control the energizing means for the light source.

11. A vanity case having swingingly connected sections mounted for relative movement in substantially parallel planes, a lighting unit, a circuit for the lighting unit, and annular switch means rotatably mounted about the swinging connection for controlling the circuit, said switch means being normally open when the sections are closed or only partially opened, and closed when the sections are fully opened.

15. A vanity case comprising two parts mounted for relative swinging movement in parallel planes, a lighting unit carried by one of such parts, means for energizing the unit, and means whereby the lighting unit is automatically energized in one predetermined swinging relation of the parts less than the full swinging movement and automatically deenergized in full swinging movement of the parts.

20. 13. A vanity case including a cover section, a body section, the sections being movable to open and closed relation, a lighting unit section, and means for connecting the sections for relative swinging movement, two of the sections moving outwardly relative to each other in their opening movement.

30. 14. A vanity case including a lighting unit and a plurality of sections movable to open and closed positions, two of such sections being movable relative to a single pivot mounting to independently interfit with and together inclose a third section containing a mirror to provide a unit substantially the size of such third section.

35. 15. A vanity case having sections, the sections being pivotally connected for swinging in substantially parallel planes on a single pivot arranged in the longitudinal median line of the sections, a light source in one of the sections, energizing means for the light source in one of the sections, and means arranged immediately adjacent the pivot and responsive to relative movement of the sections to control the energizing means for the light source.

GEORGE M. CRESSATY.
